United States Patent Office.

A. WILKE, OF BRUNSWICK, GERMANY.

Letters Patent No. 97,738, dated December 7, 1869.

IMPROVEMENT IN ICE-CREEPERS.

The Schedule referred to in these Letters Patent and making part of the same.

To all whom it may concern:

Be it known that I, A. WILKE, of Brunswick, (Braunschweig,) Germany, have invented certain new and useful Improvements in "Ice-Creepers;" and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

Figure 1 is the plan, and

Figure 2, the side elevation of the creeper.

The nature of my invention consists in a metallic plate, suitably arranged to be put on the heels of boots and shoes, and provided underneath with felt, for the purpose of preventing slipping when walking on ice, snow, and other smooth and slippery surfaces.

A is a metallic plate, large enough to cover the top piece of a heel, provided all around with series of holes, *a a*, for the purpose of securing the piece of felt B, with thread, wire, or other suitable material, underneath of and to the plate A.

The plate in front has a flange, C, provided with

pins D D, pointing to the rear, for the purpose of being drawn into the front part of the heel, to which the creeper is to be affixed, and is provided also with a standard, E, in the rear, said standard tapped with a female-screw thread, in which a thumb-screw pin, F, is operating, which pin secures the said plate A to the back part of the heel.

In place of pins *a a* and screw-pin F, other suitable fastenings may be attached to the plate A, for the purpose of securing the same to the heel.

The above-described creeper, when put on the heel of a boot or shoe, prevents the person wearing it from slipping when walking on ice, snow, sleet, and other smooth and slippery surfaces; the felt being the best material for the purpose.

Having thus fully described my invention,

What I claim as new, and desire to secure by Letters Patent, is—

An ice-creeper, consisting of the metal frame A, provided with the clips D and the screw F, with the felt sole B attached, substantially as described.

A. WILKE.
